UNITED STATES PATENT OFFICE.

JOHN L. McCULLOUGH, OF NEW YORK, N. Y., ASSIGNOR TO AUTOMATIC TARGET MACHINE CO., OF NEW YORK, N. Y.

TARGET APPARATUS.

No. 800,314.

Specification of Letters Patent.

Patented Sept. 26, 1905.

Application filed June 22, 1904. Serial No. 213,672.

To all whom it may concern:

Be it known that I, JOHN L. McCULLOUGH, a citizen of the United States, residing in the borough of Brooklyn, in the county of Kings and city and State of New York, have invented certain Improvements in Target Apparatus, of which the following is a specification.

This invention relates to the class of target apparatus wherein is employed an imitation firearm—such as a gun or pistol, for example—mounted on a joint which permits it to be aimed at a target and wherein on pulling the trigger the point aimed at on the target will be in some manner indicated automatically thereon. A device of this general character is shown in the United States Patent No. 708,245, granted to me September 2, 1902, and also in my pending application, Serial No. 179,892.

The object of the present invention is in the main to provide the apparatus with means for furnishing the marksman, should he so elect, with a record of his shots on a souvenir which he may take away with him—that is to say, as the device is herein shown the apparatus is provided with a coin or check controlled apparatus, and the marksman may merely place a coin in the slot to connect the operating-lever, press down the lever so as to cock the pistol, aim the latter, and pull the trigger, when the point he aimed at will appear on the target, or if he desires to take five shots and get a record-souvenir of his shots he may after putting his first coin in the slot and cocking the pistol operate the knob of the record device by hand so far as to feed forward a strip of record material—say of aluminium with miniature targets marked at uniform intervals thereon—to the proper extent to place a miniature target in place to receive the proper markings, and this plate will remain in position until he has fired five shots, when it will be automatically cut off from the strip and will drop out through a slot. The miniature target on the souvenir will then show five markings, indicating the positions on the target of the five shots made.

The present invention does not include the particular coin-controlled mechanism shown, nor is it limited thereto; but as some form of coin or check controlled mechanism will be employed one form of such mechanism has been illustrated herein and will be briefly de-

scribed in order to make clear the working of the other features of the apparatus.

In the accompanying drawings, which illustrate an embodiment of the invention, Figure 1 is a side elevation of the target apparatus on a small scale. Fig. 2 is a vertical axial section of the end of the apparatus where the firearm is mounted. Fig. 2^a is a detached perspective view of the rocker seen in Fig. 2. Fig. 3 is a view similar to Fig. 2 of the end of the apparatus where the target is situated, and Fig. 3^a is a plan view of the mechanism seen at the bottom of the target-casing in Fig. 3. Fig. 4 is an end view from the left in Fig. 2 with a part of the casing broken away to show the interior. Fig. 5 is a vertical section taken at x^5 in Fig. 3, showing a face view of the target. Fig. 6 is an enlarged face view of the record device with the parts in what may be called the "normal" position, and Fig. 7 is a similar view showing the parts in the position they assume when the apparatus is ready for making the fifth or final shot. Fig. 8 is a cross-section of a part of the casing substantially at line x^6 in Fig. 6, showing the record device in edge elevation. Fig. 9 is a plan view of the sprocket-drum which feeds the strip of record material and of a part of said strip thereon. Fig. 10 is a plan view of shears for cutting off the record-souvenir from the strip. Fig. 11 shows one of the record-souvenirs.

As the device or apparatus is herein shown as adapted for short-range firing with a pistol or with a firearm simulating a pistol, the firearm will be herein referred to as a "pistol;" but it will be understood the improvements in which the present invention resides is not necessarily limited to any extent of range nor to any particular kind of firearm.

1 designates any suitable form of casing, hollow base, or supporting-frame for the mechanism. At one end of this casing is the elevated target-casing 2. (Seen best in Figs. 3 and 5.) In the front of the casing 2 is the target 3, and at the other end of the main casing 1 is supported the pistol 4 on a universally-mounted hollow standard 5, as best seen in Figs. 2 and 4. The casing 1 may be, if desired, mounted on supporting-legs 6, Fig. 1, and the length of the casing 1 will be such as to permit the target to be placed at the desired distance from the firearm.

The standard 5, which carries the firearm, is mounted on pivots 7, (see Figs. 2 and 4,) so that it may be rocked, the pivots being set in a hollow turn-table 8, rotatable about its 5 vertical axis in a support 9 on the casing, being furnished with ball-bearings, so that it may rotate readily. This universal mounting of the standard provides for all the movements necessary in aiming the pistol, the pivots 10 10 mounting providing the up-and-down or vertical play and the turn-table providing the desired horizontal play.

Within the hollow of the pistol-frame is rotatively mounted on a horizontal axis a 15 disk 10, Fig. 2, having in its periphery a retaining-notch 11 capable of being engaged by a dog or pawl formed on the spring-trigger 12. A setting-rod 13 is coupled to the disk 10 at 14 and extends down through the hollow standard 5 and turn-table 8. Mounted in the casing is an elbow rocker or lever 16, (seen detached in Fig. 2,) which turns about a fulcrum-point 15, Fig. 2. This device is in the nature of two elbow-levers connected at 20 the fulcrum by a sleeve, and it has two upright and two horizontal arms. One horizontal arm 16^a is coupled to the setting-rod 13 and the other, 16^b, to the upper end of a strong spring 17. One of the upright arms 16^c is 25 coupled to a rod 18, which extends back through the casing 1 to the target end thereof. The functions of this rod will be herein-after explained.

Extending rigidly from the pistol-standard 30 5 to the other end of the casing where the target is situated is a marker-arm 19. This arm carries at its end a thin marker-disk 20, on which is the marker *m*. This latter may be a small round black spot on a white ground, 35 and it simulates a bullet-hole in the target.

It may be explained here that the marker *m* is so disposed with reference to the axis of the pistol and the center of the target that the pistol is always aimed at the marker and that when the pistol is aimed, for example, at 40 the bull's-eye of the target the marker *m* will be directly behind the bull's-eye. The target will be of some suitable transparent material—as glass, for example—and have the usual rings 45 and markings thereon, as seen in Fig. 5. The marker-disk, preferably white, is designed to move about in the space back of and near the target, and by preference it will be of sheet metal and be secured to the marker-arm 19 through the medium of an upright rod 19^a. In the casing 1, near the target-casing, is 50 mounted a limiting-ring 21, Figs. 3 and 5, through which the arm 19 extends, and this ring serves to limit the movements of the pistol in aiming. The arm 19 may have on it at 55 the point where it passes through the ring 21 a cushion 22 of some soft material to deaden the sound when the arm strikes the ring.

So far as has been described it will be noted 60 that the marker *m* would be always visible

through the transparent target and the person aiming the pistol would see it moving as he moved the pistol. This would destroy the illusion, and to conceal the marker a screen is employed, as will now be described.

Mounted slidably in guides on the front of the target-casing, and disposed between the target and the marker-disk is a thin opaque screen 23, preferably of sheet metal, painted white. This screen and its guides 23^a are 70 seen in dotted lines in Fig. 5. It is coupled by a link 24, Fig. 3, to a rocking arm 25, pivotally mounted at 26 in the casing and provided with a spring 27 to shift it suddenly. 75 28 28 are two cushioned limiting-stops between which the rocking arm 25 may play. This arm 25 is moved by means now to be described.

On the pivot 26 rocks an elbow-lever 29, one arm of which is coupled to the end of the 80 spring 27, whereby when said lever is rocked this end of the spring is carried to the other side of the pivotal center 26 and being under tension shifts the arm 25 suddenly to its other position, and thus shifts the screen 23. 85 If the screen be down, as in Fig. 3, it moves it up, so as to screen the marker-disk 20, and if it be up it moves it down, so as to disclose the marker *m* on the disk through the transparent target. The movement is so rapid 90 that the eye of the marksman does not detect it.

To actuate the lever 29, one of its arms is slotted, and the slot therein is engaged by a pin 30 in an arm 31 on a sleeve or boss 32, which turns about a pivot 33 near the base of the casing, Fig. 3^a, and another arm 34 on said boss is coupled to the screen-actuating rod 18, before mentioned. This rod 18 is actuated through the rocker 16.

The above mechanism is very similar in some respects to that shown in my said pending application, and the operation is as follows: The operator or marksman drops a coin or check in the coin-slot *s*, Fig. 2, and it passes down a coin-chute 35 to a position *c*. An operating-lever 36 is then depressed, when a 100 105 110 115 120 125 130 135 140 145 150 155 160 165 170 175 180 185 190 195 200 205 210 215 220 225 230 235 240 245 250 255 260 265 270 275 280 285 sound should be produced simulating in some degree the crack of a pistol. To effect this, there is a perforated metal plate 39, Figs. 3 and 3^a, mounted over an aperture *a* in the bottom of the casing, and over this a smaller metal plate 39^a, fixed at one edge only. A hammer 40 is mounted in the casing, so as to be elevated when the pistol is cocked and to be set free when the pistol is fired, the hammer striking the plate 39^a a sharp blow. The hammer is a lever fulcrumed at 41, and its rear and shorter arm has a pin 42, which couples it to an arm 43 on the sleeve 32. The pin 42 has a slotted connection with the arm 43. When a shot has been fired and the marker *m* exposed, it is obvious that any one may shift the pistol, as in aiming, and thus cause the marker to move visibly over the target, and to prevent this a brake device is employed to lock or secure the marker-disk in position until the brake is released by the cocking of the pistol for the next shot. This device comprises, as herein shown, Figs. 3 and 3^a, a guide 44, secured in the casing back 25 of the target, a brake-disk 45, the stem of which plays in said guide, a toggle device 46 back of the disk 45 and adapted to press the latter up to the marker-disk and hold the latter against movement, and a rod 47, coupled 30 at its upper end to the knuckle of the toggle device and at its lower end to an arm 48 on the sleeve or boss 32. When the screen 23 is down, the toggle holds and prevents movement of the marker-disk, and when the said 35 screen moves up the rod 47 also moves up and releases the brake. The movement of the brake-disk is very slight. It may be stated here that a brake similar to this is shown in my pending application.

40 The operating-lever 36, which is depressed for cocking the pistol, has a spring 36^a, which retracts it in the usual way with such levers. The general operation of the pistol and target having been described, the mechanism 45 whereby the marksman may obtain a souvenir or miniature target showing the results of five shots will now be described, with especial reference to Figs. 2, 2^a, 6, 7, 8, 9, 10, and 11. On the rocker 16 is an arm 16^d, Fig. 2^a, from 50 which extends an operating-rod 49, which serves to operate the souvenir device, as will be explained. On a drum 50 of any kind mounted rotatively in the casing is wound a strip of metal S, consisting of a series of 55 souvenirs A, one of which is seen detached in Fig. 11 and several connected in Fig. 9. The strip has in its edges notches *n* at the points of junction of the souvenirs and has on it a miniature target. The strip S is fed through 60 a guide 51 to and over a sprocket feed-wheel 52, rotatively mounted in the casing and down between the blades 53 and 53^a of a pair of shears, (seen in plan in Fig. 10,) where the souvenir at the end of the strip takes a position in front of a fixed block 54. The teeth

on the wheel 52 engage the notches *n* in the edges of the strip S, and the strip is fed forward to the extent of one souvenir by a knob 55, Fig. 8, on the projecting end of the journal of the wheel 52. If the marksman desires to take five shots and get a souvenir, he drops a coin in the slot and depresses the handle or lever 36, so as to cock the pistol. He is then enabled to turn the knob 55 far enough to feed down the strip S to the extent 75 of one souvenir and no more.

It will now be necessary to explain the mechanism connected with the souvenir device, particularly with reference to Fig. 6. In the periphery of the feed-wheel 52 are 80 equally-spaced notches 56, adapted to be engaged by a locking pawl or dog 57, which has a short arm 57^a and a spring 58. When this dog is moved out of engagement, the wheel may be rotated until the dog drops 85 into the next notch. A cam-lever 59, fulcrumed at 60, has a rounded upper end or head which bears on a cam-surface on the wheel 52, said surface having in it equally-spaced depressions 61. This cam-lever has a spring 90 62, which holds its head up to the feed-wheel, and at its lower end a yielding spring-shoulder 63, which takes under a stud 64 in the end of an elbow-shaped supporting-arm 65, pivotally mounted at 66. Carried by the operating-rod 49 (from the rocker 16) is a pawl 67, provided with a suitable spring 68 and supported or upheld under certain conditions by the arm 65.

Let us now suppose that the marksman has 100 deposited his first coin and proceeded to cock the pistol. In doing this the rocker 16 moves the rod 49 (to the right in Fig. 6) and causes the pawl 67 to glide over and along the arm 65, impinge on the pendent arm of the dog 105 57, and by rocking the latter disengage its nose from the notch in the feed-wheel. The wheel may now be turned by its knob; but this brings a cam-recess 61 therein under the head of cam-lever 59, and the latter will be 110 so rocked by its spring as to withdraw the spring-shoulder 63 from under the gravity supporting-arm 65, which falls, and this allows the spring of the pawl 67 to throw the latter down clear of the dog 57 and permits 115 the dog to engage the next notch in the rotated feed-wheel. When the pawl 67 falls, its nose drops into engagement with a ratchet-wheel 69, rotatively mounted on the frame and provided with a back-stop pawl 70. It 120 may be explained that this ratchet-wheel 69 has twelve teeth and three laterally-projecting studs 71, each of which corresponds to four teeth in the wheel. As this wheel is the medium which governs the cutting off of the souvenir A at the fifth shot, it may be explained, primarily, that the first shot of the five takes place before this wheel comes into action, and hence the four teeth—one for each of the four remaining shots—are included 125 130

between adjacent studs. The marking of the shots on the small target *t* on the souvenir *A* is effected by a point 72, carried by a spring-arm 73, secured through a collar 74 to the marker-arm 19. This point plays about, over, and near to the souvenir while the pistol is being aimed, and when the trigger is pulled and the rod 49 drawn back suddenly it acts through a pendent arm 75 and a coupling-stud 76 to throw forward a sliding bolt 77, which impinges forcibly on the spring-arm 73 and causes the point 72 to indent the souvenir-target at the proper point. The connection of the bolt 77 with the arm 75 is slotted, and a spring 78 is provided to withdraw the bolt a little when the momentum of the bolt shall have been destroyed. This frees the indenting-point from the souvenir. The marksman now drops another coin in the slot 20 and again cocks the pistol; but as the pawl 67 is now in engagement with the ratchet-wheel 69 and below the plane of the dog 57 the feed-wheel 52 will remain locked, but the pawl 67 will advance the wheel 69 one tooth and carry 25 the lateral studs 71 therein forward to a corresponding extent. This takes place at each shot up to the fifth. By that time a stud 71 will have been carried forward to the position seen in Fig. 7—that is to say, far enough 30 to impinge upon and depress one arm of a lever 79, which protrudes into its path.

It will here be necessary to digress and describe certain other features of the mechanism. The lever 79 is fulcrumed at 80 on the lower pendent arm of an upright lever 81, fulcrumed at 82. A suitable spring 83 holds the lever 79, Fig. 6, up against a stop-pin 84 on the lever 81, and a spring 85 holds a stud 86 on the lever 81 up to a shearing-lever 87, fulcrumed at 88 and engaging at its upper end the movable blade 53^a of the shears for operating same. On the operating-rod 49 is carried a pivoted dog 89, which is normally depressed by gravity as far as a stop 90 will 45 permit, but which may be elevated to the position seen in Fig. 7.

The operation is as follows: When the operator shall have cocked the pistol for the fifth time and the stud 71, as seen in Fig. 7, 50 shall have rocked the lever 79, the tail of this lever will uplift and support the dog 89 until it is in position to strike the pendent arm of the shearing-lever 87 at a recess *r* therein. Now when the trigger is pulled and the rod 49 moves forcibly to the left the first effect 55 will be to make the fifth indentation on the souvenir-target. Then the dog 89 will strike the shearing-lever and shear off the souvenir from the strip; but in operating the shearing-lever the lower arm of the latter, acting through the stud 86, rocks the lever 81. One effect of this is to draw the end of lever 79 clear from the pin 71, so that this arm of the lever flies up and the other drops, thus letting 60 down the dog 89 or permitting the dog to drop

at the next cocking of the pistol. Another effect is to cause the upper end of the lever 81 to impinge on the heel of the supporting-arm 65 below its suspension-point, thereby driving upward its forward end, causing the stud 64 to wipe onto the shoulder 63 by flexing its spring. The rise of the arm 65 lifts the pawl 67 up to its first position. (Seen in Fig. 6.)

There is an indicator I on the casing. (Seen 75 in Figs. 6 and 7.) This device comprises a glazed aperture at which normally appears a plate 91, having on it some suitable inscription, such as "Turn the knob." This plate is held down out of the range of vision by a light spring 92, but is thrown up and held up normally by an arm 93 of an elbow-lever, fulcrumed at 94, the other arm 95 of this lever being supported on the arm 65.

When the souvenir *A* is sheared off, it falls 85 out of the casing through an inclined chute opposite to that shown in Fig. 1. This chute is indicated at C in Figs. 4 and 8.

There may be a guide-shield 96, of thin metal, over the strip *S* where it passes over the 90 feed-wheel, as seen in Figs. 6 and 7, said shield extending from the guide 51 to the shears.

As the coin or check controlled device is not claimed herein, it will not be necessary to describe it any further than to say that the sliding hook 37 in the lever 36 is drawn out a little by an incline on the stop-pin 97, Fig. 2, and when a coin is dropped into the point *c* it prevents the hook from being drawn back by its spring when the lever 36 is depressed, 100 thus compelling its hook to engage the cross-bar 38. The coin is released and falls into a suitable receptacle R in the casing.

It will be noted in the drawings that the weight of the marker-arm and marker-disk is 105 counterbalanced by a spring 98, the tension of which is regulable.

Having thus described my invention, I claim—

1. In a target apparatus the combination, 110 with a target, a firearm provided with universal mountings so that it may be aimed at the target, automatic means for visibly displaying at the target the point aimed at thereon, and automatic means for effecting a permanent 115 record of each shot.

2. In a target apparatus the combination, 120 with a firearm provided with universal mountings so that it may be aimed at the target, of automatic means for visibly displaying at the target the point aimed at thereon, automatic means for effecting a permanent record of a predetermined number of successive shots, and means for separating and detaching said record from the apparatus.

3. In a target apparatus, the combination, 125 with a target, a firearm, a universally-mounted support for said firearm, means for cocking the latter, and an arm 19, movable with firearm in aiming the latter, of a marking-point 130

72 carried by said arm, a strip of souvenir material S having miniature targets marked thereon at intervals, hand-operable means for feeding said strip into position in front of the marking-point, means for locking the strip-feeding mechanism normally, means for unlocking said strip-feeding mechanism when the firearm is cocked, and means for operating the marking-point when the firearm is discharged.

4. In a target apparatus, the combination, with a target, a firearm provided with universal mountings so that it may be aimed at the target, and means for cocking the firearm, of a feed-wheel 52, provided with a knob for rotating said wheel by hand, a souvenir-strip S, fed by said wheel, an arm 19 carried by the support of the firearm and movable therewith in aiming, a marking-point 72, for marking the souvenir-strip, its spring-arm 73, carried by the arm 19, a dog 57, which locks the feed-wheel normally, means for shifting said dog to unlock the feed-wheel when the firearm is cocked, means for operating the marking-point when the firearm is discharged, and means for cutting a souvenir from the strip when the firearm is discharged.

5. In a target apparatus, the combination, with a target, a firearm having universal mountings so that it may be aimed at any part of the target, and means for cocking said firearm, of means for producing and detaching a souvenir-record of a predetermined number of successive shots fired, said means comprising a rocker 16, a spring 17 for rocking the latter when the trigger is pulled, the setting-rod 13, connecting an arm of said rocker with the firearm, the operating-rod 49, coupled at one end to an arm of said rocker, a pendent arm 75 to which the other end of the rod 49 is coupled, an arm 19, carried by the mounting of the firearm and movable therewith in aiming, a marking-point 72 carried by the arm 19, a block 54 in front of said point, a feed-wheel 52, operable by hand for feeding a strip of souvenir material between the marking-point and the said block to receive a record-mark, a spring-dog 57, engaging notches in the feed-wheel to lock it against rotation, a pawl 67 carried by the bar 49 for releasing the said dog, a hinged supporting-arm 65 for said pawl, a cam-lever 59 having a head engaging a cam-surface on the feed-wheel and

provided with a spring-shoulder supporting the arm 65, a ratchet-wheel 69, to be actuated by the pawl 67, said wheel being provided with studs 71, a pendent lever 81, provided with a stud 86, a lever 79, fulcrumed on the lever 81 with one arm in the path of the studs 71, shears for cutting a souvenir from the strip, a lever 87 for operating said shears and also the lever 81 and arm 65, a dog 89, carried by the bar 49 and adapted to be lifted into operative position by the lever 79, and a bolt 77, for actuating the marking-point when the trigger is pulled, said bolt being operatively connected with the arm 75.

6. In a target apparatus, the combination, with a transparent target, a pistol or the like, a universally-mounted support for the pistol, a marker-disk back of the target and having on it a marker, said disk being connected with and movable with the pistol-support, an opaque screen movable between the marker-disk and the target, and means for actuating the said screen when the pistol is cocked and fired, said means comprising a rocker 16, a setting-rod coupling an arm of said rocker with the disk 10 of the pistol, the spring 17 coupled to the rocker, the arm 25 which actuates the screen, the link coupling said arm to the screen, the limiting-stops 28 for the arm, the lever 29, the spring 27, coupling the arm 25 to one arm of said lever 29, a rod 18, coupled at one end to an arm of the rocker 16, and means connecting the other end of the rod 18 with the lever 29 for rocking the same.

7. In a target apparatus, the combination with the pistol having a notched disk 10, the trigger engaging said disk, the setting-rod 90 coupled at its upper end to said disk, the rocker 16, to which the setting-rod is coupled at its lower end, the spring 17 coupled to the rocker, the rod 18 coupled to the rocker, the sleeve 32, provided with an arm 34 coupled to the rod 18, the fulcrumed, lever-like hammer 40, the sounding-plate for the hammer to strike, and the arm 43 on the sleeve and coupled to the hammer for actuating the same.

In witness whereof I have hereunto signed my name, this 16th day of June, 1904, in the presence of two subscribing witnesses.

JOHN L. McCULLOUGH.

Witnesses:

HENRY CONNETT,
BENJAMIN H. HOLT.
